(57) **CLAIM**

The ornamental design for a footwear upper, as shown and described.

DESCRIPTION

FIG. 1 is a front perspective view of a footwear upper, showing the new design; and,

FIG. 2 is a right side elevational view thereof.

The even broken lines depict portions of the article and form no part of the claimed design. The dot-dash broken lines within the shaded portion of the article show stitching, which forms no part of the claimed design. Color also forms no part of the claimed design.

1 Claim, 2 Drawing Sheets
